UNITED STATES PATENT OFFICE.

WILLIAM D. FORSYTH, OF YOUNGSTOWN, OHIO, ASSIGNOR TO RAILWAY PRODUCTS CORPORATION, OF BUFFALO, NEW YORK, A CORPORATION OF NEW YORK.

CAR-TRUCK SIDE FRAME.

1,125,298.

Specification of Letters Patent. Patented Jan. 19, 1915.

Application filed June 1, 1914. Serial No. 842,155.

To all whom it may concern:

Be it known that I, WILLIAM D. FORSYTH, a citizen of the United States, and a resident of the city of Youngstown, county of 5 Mahoning, and State of Ohio, have invented a new and useful Improvement in Car-Truck Side Frames, of which the following is a specification.

The principal object of my invention is 10 to produce a car truck side frame which will be light and yet strong and which can be cheaply and easily made.

In the accompanying drawings, which form part of this specification and in which 15 like reference characters refer to like parts throughout the several views, Figure 1 is a side elevation of a car truck side frame embodying my invention; Fig. 2 is a top plan view of the side frame shown in Fig. 1; Fig. 3 is an end elevation of the side frame shown in Fig. 1; Fig. 4 is a section on the line 4—4 of Fig. 1; Fig. 5 is a side elevation of a modified form of construction of 20 a side frame embodying my invention; Fig. 6 is a section on the line 6—6 of Fig. 5; Fig. 7 is a plan view of the blank from which the compression member of the side frame shown in Fig. 1 is made; Fig. 8 is a side elevation of the finished compression 25 member; Fig. 9 is a plan view of the blank from which the tension member of the side frame shown in Fig. 1 is made; Fig. 10 is a plan view of the finished tension member; and Fig. 11 is a side elevation of the finished tension member.

The car truck side frame shown in the accompanying drawings comprises a compression member 1, a tension member 2, and a bolster guide frame 3. The compression 30 member 1 is made from a metal plate, the longitudinal edge portions of which are trimmed or sheared away to form a blank 4. The blank 4 has a general rectangular outline and is wider near its ends than at its 35 middle or ends, as shown in Fig. 7. The longitudinal edge portions of the blank 4 are bent at right angles to said plate along lines 5 parallel to the edges, to form flanges 6 projecting in the same direction from 40 the blank 4. In the same operation in which the flanges 6 are formed by bending the longitudinal edge portions of the blank 4, or in a subsequent operation, the blank 4 is bent along two parallel lines (indicated

by the dotted lines 7) which extend longitudinally of the blank 4 equally distant from the longitudinal median line thereof into a channel-shape in which the flanges 6 project in opposite directions. In the same operation that the blank 4 is bent into the 55 channel shape, or in a subsequent operation, said blank is bent along transverse lines. After the blank 4 has been bent along transverse lines, it has two straight end portions 8, a middle straight portion 9, which lies 60 in a plane parallel to the end portions 8 but spaced above said end portions, and two inclined portions 10 connecting said end portions 8 and said middle portion 9. After the blank 4 has been treated as described 65 70 it is in proper form to constitute the compression member 1 of the side frame.

The tension member 2 is made from a metal plate, whose longitudinal edges are cut or sheared off to form a blank 11. The 75 blank 11 comprises two end portions 12 which are connected by strips 13 with a middle portion 14, as shown in Fig. 9. The longitudinal edge portions of the end portions 12 of the tension member 2 are bent 80 up at right angles to said end portions along parallel lines (indicated at 15) which extend longitudinally of said end portions 12 equally distant from the longitudinal median line thereof, to form flanges 16 projecting in the same direction. The longitudinal edge portions of the middle portion 14 are bent down at right angles to said 85 middle portion along parallel lines (indicated at 17) which extend longitudinally of 90 said middle portion 14 equally distant from the longitudinal median line thereof, to form flanges 18 projecting from the blank 11 in a direction opposite to the direction in which the flanges 16 project. The blank 95 11 is bent along transverse lines to place the middle portion 14 in a plane parallel with and spaced from the plane of the end portions 12. After the blank 11 has been treated as described it constitutes the tension 100 member 2 of the side frame.

The end portions 8 of the compression member 1 are placed between the flanges 16 of the tension member 2 and in contact with the upper faces of the end portions 12 of 105 said tension member 2, and the upper edges of the flanges 16 contact with the under faces of the flanges 6 of said compression

member 1. Said flanges 16 of the tension member 2 are fastened by rivets 19 to the sides of the compression member 1.

The bolster guide frame 3 is preferably cut and bent from a structural shape or plate, but it may be cast or otherwise suitably formed. In the preferred form of construction, shown in Figs. 1 to 4, the bolster guide frame 3 is made from a flanged member which comprises a web 20 and two spaced parallel flanges 21. The flanges 21 straddle the compression member 1 and the tension member 2 and are fastened thereto by rivets 22. The top parts of the flanges 21 of the bolster guide frame 3 engage the under faces of the flanges 6 of the compression member 1.

In the modified form of construction illustrated in Figs. 5 and 6, the bolster guide frame 23 is composed of cast iron or steel, and, instead of being fastened to the compression and tension members, it is cast around the middle portions of these members. When this form of bolster guide frame is used, the compression member 1^a is the same in construction as the compression member 1 above described except that the flanges 6 are omitted.

Since the compression member 1 is made from a metal plate, the shape of the blank 4 and the lines of bending can be altered so as to give any desired shape to said compression member or to obtain any desired amount of metal at any point in said compression member. The same is true of the tension member 2. The flanges 6 stiffen the compression member 1.

Considerable change may be made in the construction which is herein shown and described without departing from my invention, and I do not wish to be limited to the details of such construction.

What I claim is:

1. A car truck side frame comprising a channel-shaped compression member and a tension member fastened together at their ends, said compression member having flanges along the edges of the sides thereof, said tension member having flanges on each end portion engaging opposite sides of the corresponding end portion of said compression member, said tension member having downwardly extending spaced flanges at the middle thereof, and a bolster guide frame fastened to the middle portion of said compression member and to said downwardly extending flanges on said tension member.

2. A car truck side frame comprising a

channel-shaped compression member and a tension member having their middle portions spaced apart, the end portions of said tension member bearing against the end portions of the web of said compression member, the sides of said compression member projecting upwardly from the web thereof and having flanges along the upper edges thereof.

3. A car truck side frame comprising a tension member having spaced flanges at each end projecting therefrom in the same direction and spaced flanges at its middle portion projecting therefrom in a direction opposite to the direction in which said first mentioned flanges project.

4. A car truck side frame comprising a channel-shaped compression member and a tension member having their middle portions spaced apart, the sides of said compression member projecting upwardly from the bottom thereof, and having flanges along the upper edges thereof, said tension member having marginal flanges along each end portion thereof, which flanges are fastened to the opposite sides of the corresponding end portion of said compression member, the upper edges of the flanges of said tension member being in contact with the under faces of the flanges of said compression member.

5. A car truck side frame comprising a channel-shaped compression member and a tension member having their end portions fastened together and their middle portions spaced apart, said compression member being of greatest cross-sectional area in the region where said tension and compression members diverge, each side of said compression member having a flange along the upper edge thereof.

6. A car truck side frame comprising a channel-shaped compression member and a tension member having their middle portions spaced apart, said tension member having marginal flanges along each end portion thereof, which flanges are fastened to the opposite sides of the corresponding end portion of said compression member, each of said flanges extending inwardly beyond the point where said compression member and said tension member diverge.

Signed at St. Louis, Missouri, this 28th day of May, 1914.

WILLIAM D. FORSYTH.
